UNITED STATES PATENT OFFICE.

FRED ALBERT ODDIE, OF HAMBLE, SOUTHAMPTON, ENGLAND.

MACHINE FOR BENDING METALS.

Application filed March 29, 1926, Serial No. 98,329, and in Great Britain April 8, 1925.

This invention relates to machines for bending lengths of metal such as pipes, rods, girders or the like of the type comprising a curved former which lies on one side of the length of metal to be bent, and a bending member which lies on the other side of the length of metal, relative movement being produced between the former and the bending member such that the point where pressure is applied to the metal between the former and the bending member moves along the length of metal during the bending operation, while a fixed abutment member is provided to restrain the metal at a point in its length adjacent to but suitably distant from the portion actually being bent.

Such machines as previously constructed were only capable normally of imparting a curve of one given radius to the metal, such radius being substantially that of the former employed. It is the object of the present invention to provide a machine of the above general type in which a simple adjustment enables the machine to impart curves of various radii to the metal while employing the same bending member and former, while further, repetition work can be carried out with ease and accuracy.

To this end according to the present invention means are provided whereby the abutment member which lies on the same side of the length of metal as the bending member and is adapted to restrain the metal at a point adjacent to but suitably distant from the portion actually being bent, is caused to yield to a controlled extent as and when pressure is applied against it during the bending operation and means are provided for varying this yielding movement of the abutment member. The yielding movement of the abutment member may be varied either in extent or in direction or in both extent and direction.

Owing to the yielding movement of the abutment member the radius of the curve which is imparted to the metal is greater than that which would be imparted thereto if the abutment member were fixed and the difference between these two radii depends on the extent and direction of movement of the abutment member. Thus the purpose and effect of varying the extent or direction or both the extent and direction of movement of the abutment member is to vary the radius of the curve imparted to the metal.

The abutment member is preferably adapted to move along a fixed guide and this movement is conveniently effected by a mechanical connection between the abutment member and the member by whose movement bending is performed, the connection comprising for example a linkage connecting the abutment member to the bending member or to a member to which movement is imparted thereby, means being provided whereby the mechanism can be adjusted and if necessary the abutment member moved so as to vary the extent of the yielding movement of the abutment member. The adjustment device for varying the movement of the abutment member is preferably provided with a scale or otherwise constructed or arranged so that it can be set readily in accordance with the radius of the curve which is to be imparted to the metal to be dealt with, while the arrangement is conveniently such that in one position of the adjustment device the abutment member will be held stationary during the bending operation.

In a preferred construction the former is fixed while the bending member is so mounted and connected to or actuated by a pivoted lever that as the lever swings, pressure is applied to the length of metal by the cooperating surfaces of the former and the bending member in the desired manner. In this arrangement the abutment member may conveniently be moved along a fixed guide by a link connected at one end to the abutment member and at the other end to the pivoted lever or to a member carried thereby or connected thereto, while means are provided for varying the distance between the axis of rotation of the pivoted lever and the adjacent point of connection of the link so as to vary the extent of the yielding movement of the abutment member along its guide. Thus for example, the end of the link remote from the abutment member may be connected to a member which is movable but capable of being locked in any desired position along a guide carried by the pivoted arm. In an alternative arrangement the end of the link remote from the abutment member may be connected to one end of a rod the other end of which passes through and is longitudinally adjustable in a socket on the arm. The longitudinal adjustment may be effected by providing the rod and socket with engaging screwthreads, the longitudinal adjustment of

the rod through the socket being effected by rotation of the rod. Alternatively the adjustment may be effected by sliding the rod through the socket to which it can be locked 5 in the desired position by a set screw or the like. In either case the arrangement is preferably such that adjustment can be effected until the pivot connecting the end of the link to the lever is coaxial with the axis 10 of rotation of the lever so that the abutment member remains stationary during the bending 15 operation.

A scale and a pointer or its equivalent 20 may be provided respectively on or associated with the two relatively movable parts of the adjusting device so that this can be set readily in accordance with the radius of the curve which is to be imparted to the metal to be dealt with and for repetition 25 work. The guide for the abutment member may be in the form of an involute of the circle of which the former is an arc.

In some cases means may be provided 30 whereby during a bending operation which requires for its completion two or more movements of the bending member, the yielding movement of the abutment member will be varied or the mechanism controlling the movement adjusted automatically 35 and in a predetermined manner for the purpose of making the radius of curvature of the individual small bends imparted by each operation of the bending member different in different parts of the complete bend so that the radius of curvature of the complete bend is different in different parts thereof and a compound curve of some predetermined form is thus imparted to the metal acted upon.

40 The former and bending member are preferably so constructed and arranged that the operative portions thereof can be removed and replaced readily so as to enable formers and bending members having operative faces of different shapes to be used as required to suit the form and nature or type of the material to be operated on, while means may also be provided for varying the distance of the bending member or the 45 support therefor from the former for the purpose of enabling adjustment to be effected in this respect to suit the particular cross section of the metal to be acted upon and to ensure proper cooperation between the 50 former and the bending member.

Although in most cases the former is fixed while the bending member moves to effect the bending, in some cases and more particularly in larger machines, the bending member 60 may be fixed and the former may be moved in the desired manner. In this case the abutment member cooperates with the former to effect the bending but moves relatively thereto to an extent which is variable 65 so as to vary the curve imparted to the metal.

This arrangement has the advantage that there is no swinging movement of the free end of the metal during the bending operation such as there is in a machine having a fixed former and movable bending member so that the space required for the machine is reduced.

The invention may be carried out in various ways but one construction according to this invention is illustrated by way 75 of example in the accompanying drawings, in which

Fig. 1 is a side elevation,
Fig. 2 is a plan,
Fig. 3 is a section on the line 3—3 of Fig. 80 2, and

Figs. 4 and 5 are respectively a perspective view and a side elevation of parts of the machine.

In the construction illustrated the machine 85 comprises a support or standard A to which is bolted or otherwise secured a plate B constituting a bed plate for the operative parts of the machine. The bed plate B has mounted thereon and preferably formed integral therewith a body block B¹ to which a substantially segment-shaped former C is adapted to be removably secured, for example by pins or the like on the former engaging suitable sockets in the body block. 95 Rotatably mounted on a pivot D passing through the body block B¹ and bed plate B is a turntable D¹ provided with two radial projections D² D³ constituting arms having 100 sockets in their ends to accommodate bars D⁴ by means of which the turn table can 105 be manually oscillated about its pivot.

110 Mounted on and projecting downwards from the arm D² is a pin E the lower end of which passes through a curved groove B² in the bed plate B and is provided with a nut E¹, the groove B² acting as a guide for the lower end of the pin E during the oscillating movement of the turntable D¹. The intermediate portion of the pin E engages a slot F¹ in a member F which is provided with an undercut groove F² in its face which lies adjacent to the former, this groove F² being adapted to receive a corresponding projection F³ on a bending member F⁴ which 115 engages the former tangentially, the member F thus acting as a carrier for the bending member F⁴.

The member F is mounted on a plate G (see Figure 4) which has a slot G¹ therein corresponding to the slot F¹ in the member F and is provided with a small metal block G² at each end serving to steady the member F, the blocks G² carrying catches G³ adapted to engage pins F⁵ on the ends of the bending member F⁴ so as to hold it in position. The edge of the plate G adjacent to the former is formed as a rack as shown at G⁴ which is adapted to engage a toothed quadrant B³ on the body block B', 120 125 130

The engaging surfaces C^1 and F^6 of the former C and bending member F^4 are suitably shaped to accommodate between them the metal rod or the like—indicated at H —to be acted upon and in the construction shown are each substantially semi-circular in cross section so as to accommodate a rod of substantially circular cross section. The intermediate portion of the pin E is eccentric with respect to its end portions and the upper end of the pin is rotatably mounted in the arm D^2 and provided above the arm with a lever E^2 . It will thus be seen that by rotating the pin E by means of the lever E^2 the member F and bending member F^4 can be moved towards or away from the former C so as to facilitate the placing in position of the metal to be acted upon and to ensure proper cooperation of the faces of the bending member and former.

With the machine as thus far described it will be seen that when the turntable D^1 is oscillated the member F and former F^4 will be moved in such a manner that the point where pressure is applied to a metal rod or the like between the former C and bending member F^4 will move along the rod or the like, the correct movement of the member F being ensured and rubbing motion between the bending member and the metal being prevented by the cooperation of the rack G^4 and the toothed segment B^3 .

The metal to be acted upon is adapted to be restrained at a point adjacent to but a suitable distance from the portion actually engaging the former by an abutment member J in the form of a stop pin mounted to move in a guide slot B^4 formed in the bed plate B , and means are provided whereby the abutment member J can be caused to move along its guide to a variable extent when the turntable is rocked to effect the bending of the metal.

The mechanism for moving the abutment member may be of various kinds but in the construction illustrated a link K is provided having a slot K^1 at one end thereof through which the upper end of the abutment member J passes. The upper end of the abutment member is screwthreaded and provided above the link K with a clamping nut J^1 having an operating handle J^2 whereby the abutment member can be clamped to the link, a certain degree of variation in the point in the link at which the abutment member is clamped being allowed by the slot K^1 . The end of the link remote from the abutment member is connected by a pivot L to a slide member L^1 which is mounted on a curved guide M rigidly connected to or formed integral with the turntable D^1 . The slide member L^1 is capable of being moved along the guide M and can be clamped thereto in any desired position by a clamping nut L^2 mounted on the upper end

of a bolt L^3 which passes through the member L^1 and guide M and is provided at its lower end with a head engaging the under-side of the guide M .

It will be seen that by moving the member L^1 along the guide M the distance of the pivot L from the axis of rotation of the turntable D^1 can be varied thus varying the extent of the movement imparted to the abutment member J along its guide B^4 and in order to enable the member L^1 to be set readily so as to impart a curve of the desired radius to the metal to be acted upon, the guide M is conveniently provided with a scale as shown in Figure 2 of the drawings. Further, the arrangement is conveniently such that in one end position of the member L on the guide M the pivot L is coaxial with the pivot D for the turntable D^1 so that the abutment member J will remain stationary when the turntable is moved, while in the other end position the movement of the abutment member J is such that no restraint is applied thereby to the metal and in consequence no bending takes place. The member L^1 is conveniently provided with a handle L^4 by means of which it can readily be moved when desired.

It will be seen that with the machine above described wherein the limiting positions of the member L^1 are such that in one of such positions no movement of the abutment member takes place while in the other the movement is such that no bending takes place, in the intermediate positions of the member L^1 bending will take place and by varying the position of the member L^1 various curves having radii greater than that of the former C can be imparted to the metal.

It will be understood that since the former C and bending member F^4 can readily be removed and replaced, members having operative faces of different configuration so as to be suitable for acting upon lengths of metal of different cross section can be substituted therefor when desired. For example various interchangeable formers and bending members may be provided adapted to accommodate pipes or rods of different diameters or bars or girders of different cross section, for example girders of H or T section. Further, instead of the bending member shown in the drawings a roller of suitable shape mounted on a pivot on the arm D^2 may be employed. A bending member such as that shown is preferable, however, in most cases where thin copper or other tube or where channel or like section metal is to be bent.

In some cases instead of varying the extent of the movement of the abutment member, the same result may be obtained by varying its direction of movement, for example by providing it with a separate guide member the position of which can be varied,

while if desired both the direction and the extent of the movement of the abutment member may be variable.

It will be seen that with a machine according to this invention repetition work in which curves of various radii have to be imparted to lengths of metal is considerably simplified, since for each curve it is only necessary to set the adjusting member to the correct position on the scale in accordance with the curve to be imparted to the metal and when the formation of this curve is completed, a simple resetting of the adjusting member is all that is required to enable the machine to impart a curve of some other desired radius to another portion of the same length of metal or to another length of metal.

The details of construction may be varied within wide limits without departing from this invention.

What I claim as my invention and desire to secure by Letters Patent is:—

1. A machine for bending lengths of metal comprising in combination a curved former which lies on one side of the length of metal to be bent, a bending member which lies on the other side of the length of metal, means for producing relative movement between the former and the bending member such that the point where pressure is applied to the metal between the former and the bending member moves along the length of metal during the bending operation, an abutment member which lies on the same side of the length of metal as the bending member and serves to restrain the metal at a point in its length adjacent to but suitably distant from the portion actually being bent, means whereby this abutment member is caused to yield to a controlled extent as and when pressure is applied against it during the bending operation, and means for varying the yielding movement of the abutment member, as and for the purpose set forth.

2. A machine for bending lengths of metal comprising in combination a curved former which lies on one side of the length of metal to be bent, a bending member which lies on the other side of the length of metal, means for producing relative movement between the former and the bending member such that the point where pressure is applied to the metal between the former and the bending member moves along the length of metal during the bending operation, an abutment member which lies on the same side of the length of metal as the bending member and serves to restrain the metal at a point in its length adjacent to but suitably distant from the portion actually being bent, a fixed guide along which the abutment member is adapted to move, a linkage connection between the abutment member and the pivoted lever whereby the abutment member can be caused to move along its guide to a controlled extent when the lever is swung, and means whereby the mechanism can be adjusted so as to vary the extent of the yielding movement of the abutment member, as and for the purpose set forth.

abutment member will yield to a controlled extent as and when pressure is applied against it by the bending operation, and means for varying the yielding movement of the abutment member, as and for the purpose set forth.

3. A machine for bending lengths of metal comprising in combination a curved former which lies on one side of the length of metal to be bent, a bending member which lies on the other side of the length of metal, means for producing relative movement between the former and the bending member such that the point where pressure is applied to the metal between the former and the bending member moves along the length of metal during the bending operation, an abutment member which lies on the same side of the length of metal as the bending member and serves to restrain the metal at a point in its length adjacent to but suitably distant from the portion actually being bent, a mechanical connection between the member by whose movement the bending is performed and the abutment member such that the latter is caused to move and yield to a controlled extent as and when pressure is applied against it by the bending operation, and means for varying the yielding movement of the abutment member, as and for the purpose set forth.

4. A machine for bending lengths of metal including in combination a fixed former which lies on one side of the length of metal to be bent, a bending member which lies on the other side of the length of metal, a pivoted lever so connected to the bending member that as this lever swings the point where pressure is applied to the metal between the former and the bending member moves along the length of metal in the desired manner, an abutment member which lies on the same side of the length of metal as the bending member and serves to restrain the metal at a point in its length adjacent to but suitably distant from the portion actually being bent, a fixed guide along which the abutment member is adapted to move, a linkage connection between the abutment member and the pivoted lever whereby the abutment member can be caused to move along its guide to a controlled extent when the lever is swung, and means whereby the mechanism can be adjusted so as to vary the extent of the yielding movement of the abutment member, as and for the purpose set forth.

5. A machine for bending lengths of metal comprising in combination a curved former which lies on one side of the length of metal to be bent the operative portion of which can be readily removed and replaced so as to enable formers of different shapes to be used as required, a bending member which lies on the other side of the length of

metal also provided with a readily removable and replaceable operative portion, means for producing relative movement between the former and the bending member 5 such that the point where pressure is applied to the metal between the former and the bending member moves along the length of metal during the bending operation, an abutment member which lies on the same 10 side of the length of metal as the bending member and serves to restrain the metal at a point in its length adjacent to but suitably distant from the portion actually being bent, means whereby this abutment member 15 is caused to yield to a controlled extent as and when pressure is applied against it during the bending operation, and means for varying the yielding movement of the abutment member, as and for the purpose set 20 forth.

6. A machine for bending lengths of metal including a combination a fixed former which lies on one side of the length of metal to be bent the operative portion of 25 which can be readily removed and replaced so as to enable formers of different shapes to be used as required, a bending member which lies on the other side of the length of metal also provided with a readily removable and replaceable operative portion, a pivoted lever so connected to the bending member that as this lever swings the point where pressure is applied to the metal between the former and the bending member 30 moves along the length of metal in the desired manner, an abutment member which lies on the same side of the length of metal as the bending member and serves to restrain the metal at a point in its length adjacent 35 to but suitably distant from the portion actually being bent, a fixed guide along which the abutment member is adapted to move, a linkage connection between the abutment member and the pivoted lever whereby the 40 abutment member can be caused to move along its guide to a controlled extent when the lever is swung, and means whereby the mechanism can be adjusted so as to vary the extent of the yielding movement of the 45 abutment member, as and for the purpose set forth.

7. A machine for bending lengths of metal including in combination a fixed former having a curved operative surface which 55 lies on one side of the length of metal to be bent, a bending member which lies on the other side of the length of metal, a pivoted lever to which the bending member is so connected that when this lever swings the 60 point where pressure is applied to the metal

between the former and the bending member moves along the length of metal in the desired manner, an abutment member which lies on the same side of the length of metal as the bending member and serves to restrain the metal at a point adjacent to but suitably distant from the portion actually being bent, a fixed guide along which the abutment member is adapted to slide, a link connected at one end of the abutment member, 65 a member carried by the pivoted lever to which the other end of the link is connected whereby movement of the lever will cause movement of the abutment member along its guide, and means for varying the distance between the axis of rotation of the lever and the adjacent point of connection of the link so as to vary the yielding movement of the abutment member along its 70 guide, as and for the purpose set forth. 80

8. A machine for bending lengths of metal including in combination a fixed former having a curved operative surface which lies on one side of the length of metal to be bent, a bending member which lies on the other side of the length of metal, a pivoted lever to which the bending member is so connected that when this lever swings the point where pressure is applied to the metal between the former and the bending member 85 moves along the length of metal in the desired manner, an abutment member which lies on the same side of the length of metal as the bending member and serves to restrain the metal at a point adjacent to but suitably distant from the portion actually being bent, a fixed guide along which the abutment member is adapted to slide, a link connected at one end to the abutment member, 90 and a member carried by the pivoted lever to which the other end of the link is connected whereby movement of the lever will cause movement of the abutment member along its guide, and means for varying the distance between the axis of rotation of the lever and the adjacent point of connection of the link so as to vary the yielding movement of the abutment member along its 95 guide, the member carried by the pivoted lever and to which the adjacent end of the link is connected being provided with a scale so that the point at which the end of the link is connected to this member can readily be adjusted in accordance with the radius of the curve which it is desired to impart to the metal to be dealt with, as and for the purpose set forth. 100

In testimony whereof I have signed my name to this specification.

FRED ALBERT ODDIE
